Claims priority, application Japan, Jan. 11, 1962, 37/511
3 Claims. (Cl. 50—55)

The present invention relates to an improvement in a method of assembling shell structures consisting of trusses having twisted surface.

The trusses which have heretofore been used as members constituting a building structure have been assembled along a plane and such plane trusses have very large resistance to the load acting along the same plane, but they have disadvantage that they are very easily deformable by the load acting from a direction not on the same plane.

Such a truss forming twisted surfaces consisting of the upper cord members and lower cord members which are not in the same plane and the shearing members connecting all cord members together will constitute a so-called hyperbolic paraboloid shell structure, of which deformations in all directions are sustained at four corners so that such a truss can not easily deform in all directions according to its own characteristics and has the shell structure by itself and accordingly a building structure consisting of an assembly of a plurality of such trusses in wave form provides a very strong shell structure cooperating with the above described truss effect.

The invention is based on the above consideration and is characterized in that the lengths of the upper and lower cords which are not located in the same plane are divided in proportion respectively and the corresponding points of division of the upper cord and lower cord and also the adjacent corresponding points of division connected successively with diagonals in a form of truss to constitute a unit shell structure having a twisted surface and a number of such unit shell structure surfaces are arranged in a wave form and connected together as a unit in such manner that the joints of each upper and lower cords and diagonal members between adjacent unit shell structures surfaces meet at the same corresponding points.

For a better understanding of the invention reference is taken to the accompanying drawings, in which

FIG. 1 is a perspective view illustrating the manner of connecting several sets of unit trusses,

FIG. 2 is a plan view of the shell structure as shown in FIG. 1,

FIG. 3 is its elevation,

FIG. 4-A and -B show partial side views of its middle portion and the end portion,

FIG. 5 is an explanatory diagram of a method of proportionally dividing the upper and lower cord members,

FIGS. 6 to 11 are perspective views illustrating several embodiments of the shell structures of the invention and,

FIG. 12 is a perspective view for illustrating a form of shell structure shown in FIG. 1 with various addition members attached thereto.

Referring to the drawings, 1 represents an upper cord, 2 a lower cord, 3 and 4 diagonals.

According to the invention, the lengths AOB and A'O'B' of the upper cord 1 and lower cord 2 which are not located in the same plane are proportionally divided respectively at points l,m,n,O,n,m,l and l',m',n',O',n',m',l' and the corresponding points of division, such as l-l', m-m', n-n', O-O' and each end of cord

members 1 and 2 such as, A-A' and B-B' are connected together by means of diagonal members 3 and moreover, the corresponding adjacent points, A'-l, l'-m, n'-n, n'-O, B'-l are connected together by means of diagonals 4 to form unit shell structure surfaces T lying on twisted planes, and a number of such unit shell surfaces T are arranged in a wave form and adjacent unit shell structure surfaces T are connected together as a unit in such manner that the joints A,l,m,n,O,B and A',l',m',n',O',B' of each upper cord 1 and adjacent lower cords 2 and diagonals 3 and 4 of adjacent unit shell structure surfaces T meet at the same corresponding points.

FIG. 5 illustrates an example of a method of proportionally dividing relatively the lengths of the upper cord 15 and lower cords respectively, wherein the upper cord 1 and lower cord 2 are projected on the same plane and the point of intersection U of the lines connecting each end of the projected cords PQ and RS respectively is found, and points of intersection e',f',g' and h' of the 20 line connecting the point of intersection U and any of the points of division e, f, g, h of the cord PQ and the cord RS are found, then these points of intersection will be the points of projection of proportionally divided points of the required cord.

FIGS. 6 to 11 illustrate various kinds of shell structures to be obtained by the invention, wherein FIG. 6 represents a dome type, FIG. 7 angle shaped type, FIG. 8 single flow type, FIG. 9 an inverted umbrella type, FIG. 10 an angular umbrella type, and FIG. 11 inverted angular umbrella type.

Since edge surface of each unit shell structure surface of the shell structure embodying the invention will become a continuation of a wave form, the truss beam obtained by connecting the upper and lower ends of 35 the shell structure by tie members 5, 6 and 7 etc. as shown in FIG. 12 can carry the end portion of the shell and support the forces acting thereon. If the spacing of each upper cord member 1 is too large to the strength of a purlin selected at random the diagonal 8 and tie member 9 are connected at middle of the diagonals 3 as 40 shown in FIG. 12 in a triangular form and an auxiliary cord member 10 is supplemented to its apex, thereby enabling to construct the purlin economically. In FIG. 11, 12 represents a supporting column.

When the truss is loaded the lower cord member usually receives tensile load, whilst the upper cord is subject to a compressive load and the diagonal member should resist against a shearing force. Accordingly, a conventional truss constructed in one plane may have very 50 large strength for a load acting on the unit plane constituting the truss, but the resistance to the load having a certain angle with the unit plane is very small. On the contrary, the shell truss according to the invention, as it is so designed that the upper cord and lower cord are 55 not in the same plane the curved surfaces formed by the upper and lower cords, and the diagonal connecting these cords constitute a so-called hyperbolic paraboloid shell, of the which the deformation is resisted at four corners. Such a shell structure has characteristics that the curved surface can not deform in all directions, the surface itself having the nature of a shell structure, the wave shaped structure consisting of a combination of a number of such shell structures has very high strength and rigidity.

As above described, the invention has the following advantages:

(1) The invention has merit in that the operating quantity at high places is reduced and the process can be accelerated since a unit shell structure surface T is built on the ground and such units are assembled in parallel at high places to constitute a complete structure.

(2) The upper and lower cord members which are

not in the same plane relative to the other are arranged at a proper distance along the direction of tangent to the end of beam, so that the beam ends constitute a successive wave form and the truss beam constructed by joining these upper and lower ends respectively can support the reaction at the end of the shell.

(3) When said distance of the adjacent upper cords is too large compared with the strength of the purlin with arbitrary selected, an auxiliary code 19 supported by diagonals 8 arranged at middle of diagonals 3 and the tie members 9 connecting them can be supplemented, thereby enabling to decide the purlins economically.

(4) By suitably selecting the vertical projected distance of the ends of the upper and lower cords, the relation to the top of the pillar will be of somewhat similar construction to that of rigid joint.

(5) As a very rigid shell structure connected with each other is resulted there is no necessity of additional tie truss between trusses as in conventional trusses.

(6) By the above described reason it is advantageous that the section of member and numbers can be economized.

(7) As the unit shell structure surface T is difficult to deform it needs no special auxiliary materials which are inevitable in a conventional truss in the hoisting process in case assembling.

What I claim is:

1. A truss comprising a lower linear chord member and an upper linear chord member not sharing a plane common to said lower chord member, said upper chord member being disposed in adjacency to said lower chord member such that an imaginary longitudinal center line determined by said upper linear chord member passes through a horizontal plane through said lower chord member at a point remote from said lower chord member, and said upper chord member being spaced from said lower chord member by linear connecting members connecting said lower chord member to said upper chord member such that a first portion of said upper chord member is spaced further from the adjacent portion of

said lower chord member then a second portion of said upper chord member is spaced from the adjacent portion of said lower chord member, said connecting members comprising a first series of connecting members each joining one of a plurality of proportionally spaced points of said lower chord member with one of a plurality of corresponding proportionally spaced points of said upper chord member and a second series of connecting members joining one of said proportionally spaced points of said lower chord member with a next adjacent proportionally spaced point of said upper chord member.

2. A support structure comprising a plurality of truss members as claimed in claim 1 wherein lower chord members of truss members are secured together and upper chord members of truss members are secured together to form a shell structure comprising a plurality of trusses having a plurality of lower chord members in a plane not common to a plurality of upper chord members thereby forming a plurality of twisted planes between a lower chord member and an upper chord member.

3. A support structure as claimed in claim 2 further comprising at least one purlin disposed in a vertical plane common to said lower chord member and having supporting members joining said purlin with said connecting members of adjacent trusses.
